(57) CLAIM

The ornamental design for apparel with stretchable material as shown and described.

DESCRIPTION

FIG. 1 is a side view of apparel with stretchable material showing my new design with the stretchable material in a non-expanded state, and wherein the design is embodied in a jacket;

FIG. 2 is an enlarged side view of the apparel with stretchable material as shown in FIG. 1, with environment removed for clarity purposes;

FIG. 3 is a side view of apparel with stretchable material showing my new design with the stretchable material in an expanded state, and wherein the design is embodied in a jacket;

FIG. 4 is an enlarged side view of the apparel with stretchable material as shown in FIG. 3, with environment removed for clarity purposes;

FIG. 5 is a side view of apparel with stretchable material showing my new design with the stretchable material in a non-expanded state, and wherein the design is embodied in pants;

FIG. 6 is an enlarged side view of the apparel with stretchable material as shown in FIG. 5, with environment removed for clarity purposes;

FIG. 7 is a side view of apparel with stretchable material showing my new design with the stretchable material in an expanded state, and wherein the design is embodied in pants; and,

FIG. 8 is an enlarged side view of the apparel with stretchable material as shown in FIG. 7, with environment removed for clarity purposes.

The broken line immediately adjacent to and surrounding the photographic area defines the peripheral bounds of the claimed design and forms no part thereof. The broken lines depicting the remainder of the pants form no part of the claimed design.
